IRVING R. SMITH, OF MILWAUKEE, WISCONSIN, ASSIGNOR TO STERLING WHEEL-BARROW COMPANY, OF WEST ALLIS, WISCONSIN, A CORPORATION OF WISCONSIN

MOLDING FLASK

Application filed March 21, 1929. Serial No. 348,812.

My invention has relation to improvements in molding flasks, and the method of making the same.

It is common to form molding flasks of sheet metal having top and bottom flanges, the corners of these flanges being formed by bending around the metal at the corners of the flask, which necessarily stretches the metal, resulting in thinness at the corners, and 10 consequent weakening thereof at the corners.

It is also well known that when a flask section is placed in the jolting machine and subjected to a jolting action, or when the sand within said flask section is rammed or tamped, 15 the said flask section is subjected to severe strain.

It is therefore one of the primary objects of my invention to provide an improved flask section and method of forming the same 20 whereby the necessity for bending the metal to form the corners of the flanges is avoided, and hence increased strength and durability is thereby secured, the construction and method also being such that the flanges extend at, or substantially at, right angles to the main body portion of said flask section, forming a comparatively sharp angle to the flanges at the point of their junction with the flask section.

30 A further object of the invention is to provide an improved flask section, and method of forming the same, wherein edge flanges extend along the edges of the section except at the corners thereof, where separate corner blocks are provided forming corner continuations of the flanges, the flanges and corner blocks being welded to the flask section so as to be integral therewith.

40 A still further object of the invention is the provision of a flask section composed of two complementary parts welded together along their lines of junction, and each part being of the improved construction hereinafter set forth.

45 With the above main objects, and other incidental objects, in view, the invention consists of the parts and combination of parts, or the equivalents thereof, and the method steps hereinafter set forth.

50 In the accompanying drawing, Fig. 1 is a

view of a sheet of the metal which is used for forming one of the complementary parts of the flask section, the sheet being shown as broken away, and the view also showing the said sheet after the flanges have been properly positioned thereon, but before being united thereto, looking on the inner side of the metal.

55 Fig. 2 is a cross-section of the sheet, the opposite edges of which on the outside are cut at a bevel, the view also showing the flanges properly positioned to the upper and lower beveled edges of the sheet or plate, but before the flanges are united to said sheet or plate by electric welding, the said flanges being also shown as cut away on their outer edges at a bevel, forming in conjunction with the beveled edges of the sheet, V-shaped spaces or recesses.

60 Fig. 3 is an enlarged cross-sectional view of the sheet or plate and the upper flange, after the flange has been united by electric welding.

70 Fig. 4 is a perspective view of one of the complementary parts of the flask section, after the flanges and corners have been fully completed.

75 Fig. 5 is a detail view of one of the corner pieces employed at each corner to complete the flanged formation.

80 Fig. 6 is an end view of Fig. 5, and

Fig. 7 is a perspective view of the complete flask section, with the two complementary parts thereof united.

85 In forming one of the complementary flask sections a plate of metal 8, preferably commercial plate metal, is employed, the upper and lower edges thereof being cut to form tapered or reduced portions 9—9, preferably, but not necessarily, forming beveled edges.

90 Top and bottom inwardly extending flanges 10—10 having their outer edges of tapered or reduced form, as indicated by the numeral 11, are held against the tapered edges of the metal plate by any suitable means, and 95 form, in conjunction with the edges of the plate, spaces or recesses 12, which recesses, if the edges are cut on a bevel, are of V-shaped formation.

100 It is next necessary, in carrying out the

method of producing the flask section, to secure the flanges 10—10 to the plate or sheet of metal, and this may be advantageously accomplished by the electric welding process, 5 the welding metal filling up the spaces or recesses 12.

It will be noticed that in Fig. 1 of the drawing the upper and lower flanges are not continuous, that is, there are two breaks 10 interrupting the continuity of both the upper and lower flanges, said breaks being indicated by the numeral 13.

The next step in the method of forming the complementary flask section is to bend the 15 sheet metal plate into the U-shaped formation shown in Fig. 4 of the drawing. It will be noticed that the breaks 13 of the flanges are so located that they will be positioned at the two corners of this U-shaped part of the flask section, whereby the necessity of the 20 bending of the flanges around these two corners is entirely avoided.

It is necessary, however, to provide for 25 completing the continuity of the flanges at the corners, or, in other words, filling in the corner spaces, and for this purpose I supply curved filling blocks 14. Fig. 5 of the drawing shows a plan view of one of these filling blocks, and Fig. 6 shows an outside edge view 30 thereof. From Fig. 6, and from the dotted line in Fig. 5, it will be seen that the filling block is provided with a tapered or reduced outside edge 15, preferably on a bevel.

As shown in Fig. 4, when these filling 35 blocks are adjusted to the corners the flanges are made continuous, and it then only remains to hold said blocks in place, which is also advantageously accomplished by electric welding, the welding metal filling the space 40 between the tapered or reduced edge 15 of the block and the opposed tapered or reduced edge of the flask section at the corner thereof. It will be seen that there is produced, as a result of the foregoing operation, a flask section 45 having an integral flange extending from its entire edge, including the corners thereof, with corner bending of the flange entirely absent and unnecessary. The other complementary part of the flask sections is made 50 in precisely the same manner as above described, and Fig. 6 of the drawing shows the two complementary parts placed together and welded to each other.

At opposite ends, fittings 16—16 extend 55 across the end joints of the adjusted together parts of the flask, and are riveted to said flask parts. These fittings are tubular, to form circular openings 17 for the insertion of handles, not shown. The fittings are also provided, each, with a vertical opening 18 for the engagement therewith of a vertical pin used to connect together a plurality of superimposed flask sections.

As customary, other end handles 19 are 60 provided.

From the foregoing description, it will be seen that I provide an improved flask section so constructed as to avoid the objectionable features referred to at the outset of this specification, and which exist in other forms of 70 molding flasks.

What I claim as my invention is:

1. A flask section, comprising a metallic main body portion bent angularly to form side and end portions, edge flanges extending 75 at an angle from the main body portion, the continuity of said edge flanges being broken or interrupted at points registering with the corners of the body portion, thereby forming spaces at the corners, blocks fitting in 80 said corner spaces and disposed at an angle corresponding to the angle of the main flanged portions, and means for uniting the flanges to the main body portion, and for securing the blocks within the corner spaces. 85

2. A flask section, comprising a metallic main body bent angularly to form side and end portions, the edges of said side and end portions being tapered or reduced, edge flanges extending at an angle from the main 90 body portion, the continuity of said edge flanges being broken or interrupted at points registering with the corners of the body portion, thereby forming spaces at the corners, and blocks fitting in the corner spaces, and 95 also formed with tapered or reduced edges registering with the tapered or reduced edges of the side and end portions of the body, and a welding material filling the recesses formed between the registering tapered or 100 reduced edges of the flanges and the corner blocks, and the body portion.

3. A molding flask, consisting of two similarly constructed metallic parts united together, each part being angularly bent into 105 U-shape to form one side and portions of opposite ends of the complete flask section, and having a right angularly extending flange throughout its entire length, and characterized by the comparatively sharp angle of the 110 flange at its junction with the body portion.

4. In a molding flask, commercial plate metal side walls at an angle with respect to one another, said walls having a substantially right angularly extending flange, and 115 means for securing said flange to said side walls to form a right angular juncture between the flange and the side walls as distinguished from a weak rounded juncture formed by bending. 120

5. In a molding flask, commercial plate metal side walls at an angle with respect to one another, said walls having a substantially right angularly extending flange, a portion 125 of said flange projecting beyond the point of contact of said flange with the edge of the walls to form an angular space and means in said space for uniting the flange to the side walls.

6. A molding flask comprising a metallic 130

main body bent angularly to form side and end portions, the edges of said side and end portions being tapered or reduced, each flange extending at an angle from the body portion, and welding material filling the space formed between the tapered or reduced edges of the body portion and the flanges.

5 In testimony whereof, I affix my signature.
